WATCH MOVEMENT HOLDER

Marvin F. Clay, High Point, N. C.

Application August 22, 1945, Serial No. 612,066

4 Claims. (Cl. 81—6)

1

This invention relates to what are known in the art as movement holders, such devices being used to hold watch movements when removed from the case in order that the watchmaker may inspect and repair the same.

A number of such movement holders are in use today but depend largely on adjustments and adjustment devices that are not positive in their operations. Some of these movement holders rely on friction, others on springs and still others on both springs and friction. Of course neither springs nor friction give any positive adjustment. There is another class of such holders in which a single pair of jaws are positively moved toward and from each other. In this class of movement holders spaced means, which are fixed on such jaws, are used to grip the movement at the spaced points on opposite sides. Such holders do not provide for the positive adjustment of such jaws.

The principal object of the present invention is to provide a movement holder wherein four jaws are employed which are arranged in pairs and wherein positive adjustment may be made to the relative positions of these jaws.

A second important object of the invention is to provide a movement holder which may be used for the smallest type of wrist watches, or, when constructed in proper size, may be used for watches of larger dimensions.

A third important object of the invention is to provide a movement holder wherein the jaws are so constructed and arranged as to securely hold a movement without the possibility of its slipping out and in such manner that, under the skill of the watchmaker, no undue pressure or distortion will be given to the lower plate of the movement which is gripped by the holder.

With the above and other objects in view as will be hereinafter apparent, the invention consists in general of certain novel features of construction and combinations of parts presently to be specifically described with relation to the accompanying drawings, and particularly claimed.

In the accompanying drawings like characters of reference indicate like parts in the several views and:

Fig. 1 is a perspective view to an enlarged scale of a movement holder as constructed in accordance with this invention.

Fig. 2 is a plan view thereof.

Fig. 3 is a second perspective view taken from a different viewpoint than Fig. 1 and to a scale somewhat smaller than that figure.

2

Fig. 4 is a detail side view of one of the screws employed in this invention.

Fig. 5 is a detail side view of a second form of screw mounted herein.

Fig. 6 is an exploded view of one pair of the jaws used herein.

In the construction of the invention as herein illustrated there is provided a pair of rectangular plates 10. Through the center of one of these plates extends a screw 11 which is threaded into the said plate. This screw has a reduced end 12 which passes through a suitable opening in the other plate 10 and projects outwardly therefrom so that a knurled head 13 may be pinned thereon by a pin 14. Also one of the plates 10 has secured therein a pair of guide rods 15 which pass slideably through the other plate 10. This arrangement insures the keeping of the plates 10 in parallelism under the adjustment by the screw 11, it being plain that when the screw is rotated the threaded plate 10 is positively moved toward or from the plate 10 wherein the screw is rotatably mounted.

On each end of each plate 10 is slideably mounted a jaw 16 having a body portion 17 slotted as at 18 to receive the plate end. Moreover each of these jaws 16 is cut away as at 19 so that the jaws may be brought close together without the screw or screw head above described interfering therewith.

Also the rods 15 will, under movement of the pairs of jaws toward and from each other, pass into the cut away portions and thus not interfere with the closing closely of the jaws 16. On top of the body of each of these jaws is a lug 20 having an upwardly extending and slightly overhanging gripping portion 21. Thus there is provided four jaws and in order to move the jaws of each pair toward and from each other a screw 22 is fitted in a threaded opening in one lug 20 of each pair and this screw has a cylindrical portion 23 revolvably fitted in the other lug 20 of the pair and provided with a head 24 on the outer side of the lug and a collar 25 on the inner side of the lug. Thus

rotation of a screw 22 will move the jaws 16 of the pair toward or from each other as desired.

It will now be obvious that not only may each pair of jaws be adjusted positively toward the other pair but also that the jaws of each pair may be adjusted positively toward and from each other. Furthermore it will be observed that for irregularly shaped watches the jaws of one pair may be adjusted at a different spacing than the jaws of the other pair. When a watch movement is placed with its plate on the top surface of the

lugs 20 a manipulation of the screws 11 and 22 will be made by the watchmaker so that the plate will be firmly gripped and positively held without undue and injurious pressure being brought thereon.

What is claimed, is:

1. In a watch movement holder, a pair of rectangular plates arranged in parallel spaced relation, a screw extending centrally through said plates, said screw being journalled for free rotation and held from longitudinal movement through one of said plates and having threaded engagement with the other plate, a pair of jaw members for each plate, each pair of jaw members having confronting faces and slots extending from these faces into the members, each plate having its ends fitting into the slots of a respective pair of said jaw members, and a screw for each pair of jaw members having a head portion freely revoluble in and held from movement through one jaw member of the pair and having threaded engagement with the other member of said pair.
2. In a watch movement holder, a pair of rectangular plates arranged in parallel spaced relation, a screw extending centrally through said plates, said screw being journalled for free rotation and held from longitudinal movement through one of said plates and having threaded engagement with the other plate, a pair of jaw members for each plate, each pair of jaw members having confronting faces and slots extending from these faces into the members, each plate having its ends fitting into the slots of a respective pair of said jaw members, a screw for each pair of jaw members having a head portion freely revoluble in and held from movement through one jaw member of the pair and having threaded engagement with the other member of said pair, and a pair of guide rods fixed in one of said plates and slidably extending through the other plate.
3. In a watch movement holder, a pair of rectangular plates arranged in parallel spaced relation, a screw extending centrally through said plates, said screw being journalled for free rotation and held from longitudinal movement through one of said plates and having threaded engagement with the other plate, a pair of jaw members for each plate, each pair of jaw members having confronting faces and slots extending from these faces into the members, each plate

having its ends fitting into the slots of a respective pair of said jaw members, a screw for each pair of jaw members having a head portion freely revoluble in and held from movement through one jaw member of the pair and having threaded engagement with the other member of said pair, and an upwardly extending lug projecting from the upper end of each jaw member and having a movement supporting face and angularly disposed movement gripping faces.

4. In a watch movement holder, a pair of rectangular plates arranged in parallel spaced relation, a screw extending centrally through said plates, said screw being journalled for free rotation and held from longitudinal movement through one of said plates and having threaded engagement with the other plate, a pair of jaw members for each plate, each pair of jaw members having confronting faces and slots extending from these faces into the members, each plate having its ends fitting into the slots of a respective pair of said jaw members, a screw for each pair of jaw members having a head portion freely revoluble in and held from movement through one jaw member of the pair and having threaded engagement with the other member of said pair, an upwardly extending lug projecting from the upper end of each jaw member and having a movement supporting face and angularly disposed movement gripping faces, and a pair of guide rods fixed in one of said plates and slidably extending through the other plate, said jaw members having notches extending from their confronting faces and embracing said rods upon closing of the jaw members of the pairs on each other.
